CYLINDER ARRANGEMENT
Ansel W. Dunham, P.O. Box 242, Tilton, N.H.
Filed Feb. 13, 1962, Ser. No. 172,967
15 Claims. (Cl. 92—164)

This invention relates to improved fluid cylinders and to an improved method for assembling the same. More particularly it relates to pneumatic or hydraulic cylinders of improved construction featuring interchangeable parts, rapid convertability to a desired function, sturdy structure which is light in weight and which may be rapidly assembled and dismantled.

One of the principal features of this invention is a unique mounting construction of the heads of the cylinder to the barrel in such manner that the naturally inherent forces induced by internal pressure in the operation of the cylinder tend to lock the head even more tightly to the barrel. In this manner there is an increased retaining force between the heads and the barrel at the time of the increased internal pressure of the cylinder, whereas this force becomes less as the internal cylinder pressure subsides.

Heretofore the methods of affixing the heads to the barrel of the cylinder consist of internally threaded heads and externally threaded barrels, internally grooved heads and externally grooved barrels with some sort of a retaining ring to prevent separation, or a tie rod construction which embodies the use of very heavy heads and tie rods with all necessary brackets, lock washers, nuts, etc., and which produces a highly cumbersome, hard to assemble and to dismantle, unwieldy and generally unattractive cylinder.

The cylinder construction of the present invention provides for a finished product with a high strength-to-weight ratio, streamlined in appearance and which may be completely assembled or disassembled in a fraction of the time required of conventional cylinders, can be immediately converted to a double rod cylinder from a single rod cylinder at a minimum outlay of parts and labor to permit maintenance of a minimum dealer supply and still provide for varying bores and strokes for immediate availability to the end user. The piston head construction is a solid one-piece body to which is moulded a one-piece seal as a homogeneous unit with the body being tapped for holding the rod from opposite ends, with a dead center to eliminate all possibility of internal leakage. The outer or wall contact edges of the piston are moulded and serrated to provide a multiplicity of wiping edges, thus rendering the possibility of leakage at this point to a minimum. With the body unit of the double piston rod head tapped from opposite ends, the live end mounting screw is interchangeable with the dead end mounting screw so that if a two-rod cylinder is required, it may be obtained in a matter of minutes and at negligible cost, whereas with conventional cylinders a completely new cylinder would be needed and the replaced cylinder discarded. The live or forward end locking screw member preferably carries a square O ring with serrated edges to prevent leakage along the piston rod passing therethrough. Since the cylinder inlet and outlet orifices are cast integral with the heads which have no threaded connection to the cylinder, these orifices may be rotated to any desired degree for connection with the fluid pressure means.

Another principal object of the apparatus and method of the invention is to provide means whereby a fluid pressure cylinder may be assembled in any desired length from ordinary tube having a cylindrical wall of uniform thickness and having smooth inner and outer faces, by simply cutting the tube to the desired length and assem-

2

bling with the novel cylinder heads of the invention. The prior art step of threading or grooving the cylinder to secure the cylinder heads is eliminated by providing mechanical advantage means on each cylinder head, for piercing sharp, hard protuberances into the wall of the tube during assembly, the bite of the protuberances into the preferably softer material of the tube firmly anchoring each head against axial movement under cylinder pressure. The force exerted on the hard protuberances is preferably outward against the inner face of the tube, or cylinder, and is opposed by an encircling flange on the cylinder head, forming a rigid, unyieldable socket of predetermined depth for receiving the end of the tube, or barrel, thereby assuring that even thin walled tubes will not be deformed or fractured during the assembly operation.

For a more complete understanding of the present invention, reference is now made to the drawings wherein:

FIGURE 1 shows a cross-sectional view of the cylinder,
FIGURE 2 shows an extension used to foreshorten the piston stroke without foreshortening the cylinder,

FIGURE 2A is an enlarged somewhat diagrammatic, fragmentary view showing the sharp hard protuberances on the expansible ring piercing the softer inner face of the side wall of the cylinder to secure a plurality of anchoring bites,

FIGURE 3 is a cross section of an alternative head preferably used in hydraulic applications,

FIGURE 4 is a side view of the expandable locking ring,

FIGURE 5 is an elevational view of the locking ring expanding member, and

FIGURE 6 is a plan view of the locking ring expanding member.

Referring now to FIGURE 1, there is shown a cylinder 10 having cylinder heads 11 and 12 attached at each end through expanding locking rings 13, 14; locking ring expanding members 16, 17; and a livehead lock-up screw 18 adapted to receive the piston rod therethrough and a deadhead lockup screw 19 at the other end as will be more fully explained hereinafter. The heads become secured to the cylinder more tightly as pressure is applied internally to actuate the piston rod. The dead end lockup screw 19 is threadably engageable with locking ring expanding member 17. A split ring 22 spaces the head of the lockup screw 19 from the cylinder head 12 in the absence of a mounting member as shown. A similar split ring 23 spaces the head of the lockup screw 18 from cylinder head 11. The walls of both split rings are of a truncated, conical configuration so as to provide a smooth finished appearance as shown by split ring 22 and, by reversing the taper of the truncated conical outer surface, it locks a mounting member 24 in place as shown. The mounting member may then be fastened to a suitable structure for retaining the cylinder in a fixed position. A mounting member may be secured on the other end by simply backing up the lockup screw 19 to allow reversing of the split ring 22 over the mounting member, and re-tightening the lockup screw to secure the mounting member. Suitable input and output orifices 26 and 27 in cylinder heads 11 and 12 communicate with the interior of the cylinder through suitable passageways 28, 29 of locking ring expanding members 16 and 17. The livehead lockup screw 18 has a bushing 31 and a seal 32 through which the piston rod 33 passes. The outer end of the rod 33 is locked into a rod clevice 34 with a locked nut 36. Pin 37 connects the piston rod 33 to apparatus to be actuated thereby. Seal 32 is preferably square O ring with serrated edges to provide for a plurality of wiping surfaces.

The piston head 38 is a solid one-piece body to which is moulded the wiping seal 39 as a homogeneous unit. The piston head 38 is tapped to receive a piston rod at either end, but these tapped openings do not communicate with each other and therefore all possibility of leakage through the piston head is entirely eliminated. The serrated contacting surfaces of seal 39 provides a multiple of wiping surfaces against the inner surface of cylinder 10 to thereby provide for a very efficient seal with a minimum of leakage and pressure. It should be noticed that the seal extends laterally beyond its connection with the piston head so that internal pressure forces the seal into greater wiping contact relationship with the cylinder wall.

The serrations 40 slant inwardly from the ends and it is the trailing half of the serrations that provide the multiple wiping action. For example, when internal pressure from the left forces the piston head to the right, the pressure urges the left half of the serrations in wiping contact. This type of seal is particularly effective on scored or pitted cylinder barrels. The locking ring expanding members 16, 17 have a circular extension 41 which cooperates with the cushioning wall 42 of piston head 38 to provide a cushioning when the piston has reached its end of the stroke. Fluid trapped therebetween may escape through suitable openings 43 to permit the piston to complete its stroke. These openings may be made adjustable in size to provide controlled escapement as desired or they may be preselected in size.

In FIGURE 2 there is shown an extension 44 which is threadably insertable into opening 46 of dead head lock-up screw 19. The threaded shaft 47 may be of any desired length and the cylindrical extension 48 also may be of a desired length to stop the piston head 38 when it passes within the cushioning wall 42 thereon.

As shown in the cross-sectional view in FIGURE 3 of an alternate head construction, the cylinder 10 is gripped on the inner wall with the locking ring 13 in a manner similar to that shown in FIGURE 1. The cylinder head 12a, however, has an inner tapered recess 49 in which is positioned another locking ring 50 to additionally grip the outer surface of cylinder 10. This recess 49 is longer than the locking ring 50 contained therein to permit lateral movement thereof. This lateral movement of the ring against the tapered recess causes further inward movement of the ring against the cylinder. Thus, as the internal cylinder pressure increases, the gripping pressure to retain the cylinder head on the cylinder also increases. For this reason, this embodiment is preferably used in hydraulic pressurization involving higher pressures.

Referring back to FIGURE 1, it should be noted that as the lock up screws 18 and 19 are tightened, the locking ring expanding members 16 and 17 move outwardly, and with their tapered outer surface they urge the locking rings into tighter gripping relationship with the cylinder 10. As the internal pressure increases, there is a tendency for the cylinder heads 11 and 12 to move longitudinally away from the cylinder barrel 10. This in turn causes the locking ring expanding members 16 and 17 to be urged outwardly thereby increasing the locking ring contact with the inner wall of the cylinder 10 to thereby provide a greater gripping effect, thus withstanding the greater forces to which the cylinder heads have become subjected.

FIGURE 4 is a side view of the locking ring. This thin side-walled tubular steel ring has an inner surface 51 tapered approximately seven degrees to present a truncated, conical space to receive the locking ring expanding members 16 or 17 that are adapted to fit therein. The outer surface 52 is cylindrical in form and has buttressed threads for engaging the inner wall of the cylinder. A buttressed thread is defined as one that has an outwardly extending side and a tapered side. The tapered side 53 slopes outwardly toward the same end 54

of the ring as the smallest diameter 56 of the inner surface 51. Other knurled or friction surfaces also may be used. The walls 58 of the ring are slotted alternately from opposite ends of the ring to predetermined depths to achieve flexibility. One slot 59 extends from end to end to permit the expansion and contraction of the ring.

FIGURE 5 and FIGURE 6 is a plan and elevational view of the locking ring expanding member 16. This consists of an internally threaded nut 61 with a truncated, conical exterior surface 62 cooperatively engageable in a mating pitch with the inner surface 51 of the locking ring 13 (see FIGURE 4) whereby lateral movement of the nut will cause outward expansion of the ring to grip the inner surface of the cylinder wall. It has an outwardly directed end 63 extending toward the end of the cylinder and an inwardly directed end 64 extending toward the center of the cylinder. The inwardly directed end has a cylindrical extension or male ring 41 machined thereon which mates with the cushioning wall 42 in the piston head 38 (see FIGURE 1) to achieve a cushioning effect. The fluid entrapment therebetween is controlled through the opening 43 in the piston head 38. Extending inwardly from the outwardly directed end 63 of the expanding member 16 is an annular bottomed groove 66 between the threaded inner surface 67 of nut 61 and the conical surface 62. Axially extending slots 68 extend from the outer surface 62 inwardly to the inner edge of the groove 66. The groove 66 and slots 68 provide flexibility in the external surface 62 to provide a continuous pressure action on the locking ring 13 that would not otherwise be obtainable with a non-resilient type member.

As best shown in FIGURE 2A, the cylinder barrel 10 may be cut to the desired length from ordinary tube having a cylindrical wall 70 of uniform thickness, a smooth, ungrooved, unthreaded, outer face 71 and a smooth, ungrooved, unthreaded, inner face 72. Each cylinder head, such as 12 is provided with a flange 73 encircling the adjacent end of the barrel 10 for resisting and opposing outward pressure especially when the wall 70 is relatively thin. The inner face 74 of each flange 73 is smooth for slidably engaging and fitting the outer face 71 of the end of the barrel 10 seated within the head 12 and includes an annular groove 75 for a seal such as the O-ring 76.

The outwardly expandable anchoring ring 13, when in its normally contracted condition, slides within the end of barrel 10, but is provided with the plurality of sharp, hard protuberances indicated at 78 and formed by the buttressed threads 79 or by equivalent metal piercing elements. Upon exertion of outward radial pressure by the mechanical advantage means 80, which preferably consists of the expanding member 17 operable by the threaded lock-up screw 19 from the outside of the head, the sharp, hard edges, or points, 78 pierce into the inner face 72 to firmly anchor the head against axial movement relative to the barrel. Each head such as 12 includes a smooth axial bore 20, having a suitable fluid seal 21 therein, in which the lock-up screw such as 19 is turnable and slidable.

The lock-up screw, or bolt, 19 is tapped at 82 for convenience in mounting the cylinder or mounting other parts on the cylinder.

It will be understood that the material of the sharp, hard protuberances 78 is of a hardness sufficient to bite or gouge, a minute distance below the plane of the inner face 72 of the barrel 10 although it is not necessary that each protuberance pierce an equal distance or that all protuberances secure an identical grip. While merely roughened metal to metal surfaces, with substantial outward force, normal to the axis of the barrel 10, and exerted by mechanical advantage means 80, might create sufficient boundary friction to make a satisfactory low pressure cylinder, such frictional gripping means, is not contemplated herein. In the method and apparatus of this invention, the cylinder heads are each firmly

anchored against axial movement by an actual penetration into the material of the barrel to the extent that they cannot be moved while the expansible ring is in expanded condition despite internal pressures of 150 p.s.i. or more.

It has been found that a barrel 10, cut from a tube of relatively soft metal such as tool steel or manganese steel and an expansible ring 13, with sharp teeth or protuberances 78 of relatively hard metal such as high carbon steel, when assembled into a cylinder in accordance with the invention with the outward pressure exerted by the mechanical advantage means 80 will have an indentation, or impression, 83 with a depth which is perceptible to the human eye in the form of a shallow, sometimes interrupted annular groove for each annular protuberance. A cylinder, so made, has been operated under a fluid pressure of 150 p.s.i. continuously for several months with no leakage and with no axial movement of the heads.

It will also be understood that while the inner face of the barrel may show no marks at all when the device is disassembled after use, the expanding protuberances may have created a deformation therein which resumed its original shape upon release of pressure. It is believed that the outward pressure of the expanding locking rings increases during increase of pressure within the barrel by an outward movement of the expanding members which is imperceptible and therefore not shown.

It is my theory that the seven degree inclined mating surfaces, when polished, lubricated or sleeved with "Teflon" will convert a one pound axial pull on the expanding member 16 into at least a 4.32 pound outward force against the inner face of the barrel 10. Where the steel barrel 10 is about three inches in inside diameter and .062 inch in thickness, the circumferential stress on the barrel may then be calculated by the formula

$$St = \frac{\text{Internal pressure} \times \text{inside diameter}}{2 \times \text{barrel wall thickness}} =$$

$$\frac{4.32 \times 3}{2 \times .062} = 70.12 \text{ p.s.i./lb. pull on expanding member}$$

If 60,000 p.s.i. is taken as a safe circumferential stress for a cylinder tube then

$$\frac{60,000}{70.12} = 840 \text{ lb. = safe pull on expanding member}$$

A safe torque on the lock-up screw 19, to achieve up to an 840 lb. pull on the expanding member, has been calculated to be up to about 78.5 inch pounds.

Whether the sharp edges, or points, 78 make a temporary deformation or a permanent deformation in the inner face of the barrel, it will be apparent that the cylinder heads 11 and 12 are firmly anchored against axial displacement when sufficient torque is applied to the locking screws, with little danger of rupture of the barrel, especially in view of the encircling flange 73 on each head.

While my invention concerning the utilization of self-induced locking forces to oppose the pressures of separation has been explained in connection with the retention of heads on an actuation cylinder, this same principle may be applied in other areas such as in joining or coupling of pipes or tubing, or closures to pressure vessels of any size.

The step of the method of my invention wherein the cylinder barrels may be cut from commercially available seamless tubing of any desired diameter and wall thickness permits a local dealer to fill orders for fluid cylinders without delay. Because the resulting cylinder barrels need not be threaded, or grooved, to retain my improved cylinder heads, costly machinery need not be used to affix the heads and the wall thickness of the tubing may be at a minimum.

Having thus described the invention and the embodiments thereof, it is desired to emphasize that many modifications may be resorted to in a manner limited only by a just interpretation of the following claims.

5 What is claimed is:

1. An improved high strength-to-weight cylinder comprising:

a cylinder barrel having smooth inner and outer walls, cylinder heads at each end of said barrel, each having a smooth axial bore and having an integral annular flange of predetermined length forming a socket slidably receiving an end of said barrel and adapted to resist outward pressure, pressure openings in said heads to pass pressure fluid into said cylinder barrel, said cylinder heads normally being urged outwardly by internal pressure within said barrel, means at each opposite end of said barrel for retaining said heads on said barrel ends, each said means comprising:

an outwardly expansible locking ring of hard metal, within the socket of each said head, said ring having sharp protuberances engaging the inner cylinder barrel wall opposite the flange of said head,

a locking ring expanding member for urging outward expansion of said locking ring against said inner wall, and

a lockup screw in said axial bore, and operable from outside said head for drawing together said cylinder head and said expanding member to thereby cause said locking ring to expand against said barrel within said socket.

2. The improved cylinder as defined in claim 1 wherein said locking ring expanding member has a truncated conical configuration with a tapered outer surface having a plurality of radially extending slots therein for resilient flexibility thereof, and

said locking ring has a truncated conical inner surface having a plurality of slots extending alternately from each opposite end thereof for receiving said expanding member therein, and

wherein the tapered outer surface of said locking ring expanding member mates with said locking ring inner surface.

3. The improved cylinder as defined in claim 1 wherein said locking ring expanding member includes a plurality of radially extending dead end slots, each extending alternately from an opposite end thereof for resilient flexibility, and whose inner configuration is an internally threaded nut for receiving said lockup screw.

4. The improved cylinder as defined in claim 2, wherein said locking ring expanding member has orifices therethrough to permit fluid flow from the pressure openings in said cylinder heads to the interior of said cylinder barrel.

5. The improved cylinder as defined in claim 1 wherein said ring is formed of one piece of hard steel with a truncated, conical, inner surface having a longitudinal slot extending across said ring to permit expansion, and partial slots extending inwardly from alternate ends of said ring for flexibility to thereby permit the outward expansion of said ring to engage said inner cylinder wall.

6. The improved cylinder as called for in claim 1 wherein a truncated conical split ring is used to properly space the head of one of said lockup screws from its associated cylinder head, and wherein said truncated conical ring may be inverted to thereby retain a mounting member.

7. An improved high strength-to-weight piston cylinder comprising
a cylinder barrel having a cylindrical wall of uniform thickness with smooth inner and outer faces;
a pair of cylinder heads, each having a flange encircling one of the opposite ends of said barrel and forming

a socket of predetermined depth for resisting outward pressure, a smooth inner face on said flange engaging the smooth, outer face of said wall and a fluid passage communicating with the interior of said barrel, and

means for retaining said heads on the ends of said barrel, said means comprising

an outwardly expansible anchoring one piece, metal, ring within each said head, said ring having a plurality of sharp, hard protuberances on the outer face thereof in engagement with, and adapted to pierce into, the inner face of the portion of said wall within said socket and

mechanical advantage means mounted on each said head and operable from the outside thereof, said means being operably connected to said anchoring ring to outwardly expand the same for piercing said protuberances into said wall thereby firmly anchoring said heads against axial movement relative to said barrel.

8. The improved cylinder as defined in claim 7 wherein said anchoring ring includes a tapered, slotted inner face and said mechanical advantage means comprises an axially movable expanding member having a tapered, slotted outer face in engagement with the inner face of said ring and having fluid passageways centrally thereof and threaded mechanism for drawing together said cylinder head and said expanding member to thereby expand said ring outwardly.

9. The improved cylinder as defined in claim 7 wherein said barrel is of metal and

30 said protuberances are a plurality of axially spaced buttressed threads, each terminating in a sharp annular edge of hard steel at least equal in hardness to the metal of said barrel.

10. An improved fluid pressure cylinder and head structure comprising:

a cylinder barrel having a cylindrical wall of uniform thickness with smooth outer and inner faces;

a cylinder head having an integral, annular flange slidably fitting around and encircling the outer face of one end of said barrel, said flange extending longitudinally therewith a predetermined distance to resist outward pressure of expansible retaining means within said end of said barrel, and

45 said expansible retaining means within said end of said barrel, said means including

an outwardly expansible locking ring formed of one piece of hard metal having a series of sharp hard protuberances extending longitudinally and circumferentially therearound in engagement with the smooth inner face of the portion of said barrel encircled by said flange,

50 and mechanical advantage means on said head, operable from the outside thereof, said means being operably connected to said ring to outwardly expand the same for piercing said protuberances into said wall and anchoring said head to said barrel.

11. The structure defined in claim 10 wherein said head includes a fluid passage communicating with the interior of said one end of said barrel and said mechanical advantage means includes a fluid passage connecting said one end of said barrel to the remainder of the interior of said barrel.

12. The improved cylinder as defined in claim 1 wherein the lock-up screw in the cylinder head at one end of said barrel is dead head with a threaded deadend opening in the inner face thereof and the lock-up screw in the cylinder head at the other end of said barrel includes a smooth axial bore for slidably receiving a piston rod.

13. The improved cylinder as defined in claim 1 wherein in said locking ring expanding member includes a truncated conical exterior surface having axially extending slots for providing resiliency and an inwardly directed end having an unslotted central portion with a cylindrical extension thereon for mating with a corresponding portion of a piston head.

14. The improved cylinder as defined in claim 12 plus a detachable member having a cylindrical extension thereon for mating with a corresponding portion of a piston head on said piston rod and having a threaded shaft insertable in said deadend opening in said lock-up screw.

15. The improved cylinder as defined in claim 10 plus: an inner tapered surface in the flange of each said cylinder head forming an inner tapered recess therein, and an inwardly contractable locking ring, positioned within said recess, said ring having sharp, hard protuberances in engagement with the smooth outer face of the portion of said barrel encircled by said flange, and having an outer tapered surface mating with the inner tapered surface of said flange; whereby normal tendency toward lateral movement of said head due to increased inner cylinder pressure causes said locking ring to contract inwardly more tightly around the end of said barrel.
